[57] **ABSTRACT**

A hydraulic pump of the intermeshing spur gear type has a one-piece liner for the gear cavity in the body. The liner is a C-shaped piece of resilient metal coated with bearing material and in its free state, is larger than the cavity and requires elastic compression to be inserted therein. The inlet passage is formed with three branches for improved filling at high speeds.

REMOVABLE LINER FOR GEAR PUMP

High pressure hydraulic gear pumps require, for efficient operation, that there be a very close running fit between the tooth peripheries and the circular walls of the body cavity in which they run. This fit is often accomplished by a running-in process which necessitates using a body of softer metal and therefore of lower strength. This close fit gradually deteriorates as the parts wear, and eventually the pump becomes unserviceable. Because of the relative hardnesses, it is the body which wears out rather than the gears, and it is usually economically unfeasible either to salvage the body or to replace it with a new one.

It has been proposed to provide a removable liner for the gear pump body which can be replaced when worn. However, previous attempts to do this have failed because of the difficulty of holding the liner in place against the fluid pressure forces acting upon it. These tend to get behind the liner, that is between the liner and the body, and cause premature wear, as well as allowing leakage from outlet to inlet behind the liner.

Another difficulty with previous gear pumps lies in their limited speed potential due to cavitation occurring at the inlet. A proposal to alleviate this problem is disclosed and claimed in the application of Pettibone et al., Ser. 63,192, filed Aug. 12, 1970 for Power Transmission. The branched inlet passage there disclosed is satisfactory for pumps up to certain limits of tooth depth to width ratios, but beyond this, the filling efficiency tends to fall off.

The foregoing difficulties are overcome by the present invention which comprises a hydraulic pump with a body having an ovoid cavity, a pair of intermeshing gears mounted to rotate in the cavity, inlet and outlet passages in the body, the inlet passage being branched to enter the cavity at the end faces of the gears, and a liner for the ovoid surface of the cavity comprising a single piece of resilient sheet material extending in contact with the tooth peripheries of both gears and across the area adjacent the inlet, but having free ends providing an opening adjacent the outlet, the liner having a preformed free shape larger than the cavity and being elastically compressed at its free ends to fit the cavity.

The invention further comprises such a pump wherein the inlet passage includes a third branch extending perpendicular to the plane containing the gear axes and entering the cavity midway between the end faces of the gears.

IN THE DRAWINGS

FIG. 1 is a transverse cross section of a gear pump embodying a preferred form of the present invention.

FIG. 2 is a fragmentary cross section on line 2—2 of FIG. 1.

FIG. 3 is a side view of a liner incorporated in the pump of FIG. 1.

FIG. 4 is a view of the liner as seen from the plane 4—4 of FIG. 3.

FIG. 5 is a cross section on line 5—5 of FIG. 3.

FIG. 6 is a cross section on line 6—6 of FIG. 3.

FIG. 7 is a perspective view of a portion of the pump body and liner adjacent the inlet.

Referring to FIG. 1, the pump comprises a body 10 having an ovoid cavity 12 within which the usual pair of meshing gears 14 is mounted for rotation. An inlet

passage 16 and an outlet passage 20 are provided in the body. As seen in FIG. 2, the inlet passage 16 has a pair of lateral branches 18 which feed fluid to the end faces of the gear teeth and, more importantly, to the interdental spaces. A third branch 22 extends straight inwardly to the cavity 12 to carry a small portion of the total inlet stream inwardly to a point midway between the end faces of the gears.

The cavity 12 is provided with a liner 24 which is of generally C-shaped configuration. It is illustrated in detail as a separate piece in FIGS. 3 through 6 inclusive. The liner is preferably formed from sheet steel of a resilient or springy nature and is provided with a coating 26 of aluminum or other bearing material suitable for low friction contact with the tooth tips of the gears 14, and capable of wearing in to a close fit with them. As illustrated in FIG. 3, the liner, in its free state, is formed to be somewhat larger than the cavity 14. Thus, in order to insert the liner into the cavity, the liner has to be compressed to the shape illustrated in dot-dash lines and then pushed into the cavity. This results in a tight contact between liner and cavity with the highest pressure of contact existing at the two open tips of the liner where it is exposed to the highest fluid pressure.

Adjacent the third inlet branch 22 where it passes through the liner, the latter is provided with a pair of shallow depressions 28 for assisting in the induction of fluid from the branches 18 and 22 to the interdental spaces. These depressions become progressively more shallow toward their ends more distant from the inlet 22. By this configuration, it has been found that filling efficiency is increased apparently due either to an effect similar to that of an impeller pump or to an injector effect somewhat analogous to a venturi, or to both.

The pump will include the usual additional elements of construction such as bearings, drive shafts, seals, cheek plates, covers, and mounting flanges, all of which may be of known construction and are not illustrated in the present drawings.

We claim:

1. A hydraulic pump comprising a body having an ovoid cavity, a pair of intermeshing gears mounted to rotate in the cavity, inlet and outlet passages in the body, the inlet passage being branched to enter the cavity at the end faces of the gears, and a liner for the ovoid surface of the cavity comprising a single piece of resilient sheet material extending in contact with the tooth peripheries of both gears and across the area adjacent the inlet, but having free ends providing an opening adjacent the outlet, the liner having a preformed free shape larger than the cavity and being elastically compressed at its free ends to fit the cavity.

2. A pump as defined in claim 1 wherein the liner is formed of sheet steel having an adherent layer of bearing material on its inner surface.

3. A pump as defined in claim 2 wherein the layer is an aluminum alloy.

4. A pump as defined in claim 1 wherein the inlet passage includes a third branch extending perpendicular to the plane containing the gear axes and entering the cavity midway between the end faces of the gears.

5. A pump as defined in claim 4 wherein the liner contains shallow depressions extending from the end of the third inlet branch in the direction of gear rotation.

6. A pump as defined in claim 5 wherein the depressions are progressively shallower toward their distant ends.
